UNITED STATES PATENT OFFICE.

ELIZABETH W. WRIGHT, OF PHILADELPHIA, PENNSYLVANIA.

DESIGN FOR A PUZZLE-BOX.

No. 38,502.

Specification for Design.

Patented April 2, 1907.

Application filed February 20, 1907. Serial No. 358,507. Term of patent 7 years.

To all whom it may concern:

Be it known that I, ELIZABETH W. WRIGHT, a citizen of the United States, residing in Philadelphia, Pennsylvania, have invented a new, original, and ornamental Design for a Puzzle-Box, of which the following is a specification.

In the accompanying drawings, forming part of this specification, Figure 1 is a per-

spective view of my new design for a puzzle, and Fig. 2 is a plan view of the same.

I claim—

The ornamental design for a puzzle, as shown.

ELIZABETH W. WRIGHT.
